UNITED STATES PATENT OFFICE.

BENJAMIN WEXLER, OF BROOKLYN, NEW YORK, ASSIGNOR TO THE PEELE COMPANY,
OF BROOKLYN, NEW YORK, A CORPORATION OF NEW YORK.

ELEVATOR-DOOR.

1,237,431.

Specification of Letters Patent. Patented Aug. 21, 1917.

Application filed June 15, 1916. Serial No. 103,703.

To all whom it may concern:

Be it known that I, BENJAMIN WEXLER, a citizen of the United States, residing at the borough of Brooklyn, city of New York, county of Kings, and State of New York, have invented certain new and useful Improvements in Elevator-Doors, of which the following is a specification, reference being had therein to the accompanying drawings, which form a part thereof.

My invention relates to elevator doors and more particularly to a type of doors known as "truckable doors" wherein a vertically sliding door or section thereof is so controlled as to bring the top thereof substantially flush with the door sill to bridge the gap between the car platform and the sill.

Ordinarily in doors of this character stops are provided upon the guide rails at each side of the door opening, so as to arrest movement of the door or door section when in the proper position, the material of the door itself being relied upon in large measure to resist the strain upon the truck bar intermediate said stops. At the present time, however, fireproof elevator doors are being largely made of metal frames having corrugated sheathing. This type of door is comparatively light in structure and unsuited to withstand the load placed upon the top bar of the frame or a truck bar carried thereby.

By my invention I provide a truckable elevator door which may have a light metallic structure throughout, if desired, the stresses of loads passing across the truck bar from the floor of a building to the elevator platform, being transmitted to the wall of the elevator shaft instead of being sustained by the door structure and the stops carried by the rails upon which the door has vertical movement. In this manner the load upon the truck bar may be distributed across substantially the entire width of the door opening, thus minimizing any tendency toward a disarrangement of the side rails as well as relieving the suspension means from all stresses from the loads passing over the truck bar. I also combine in this structure a binder mechanism between the car and the lintel preventing swaying of the door, both while the door is open and while it is closed.

To secure the desired strength in the support for the truck bar when the door is open, it is necessary to project said support within

the plane of movement of the frame of the door, said door being necessarily so constructed as to permit the free movement of the door past said support while insuring the proper relative positions of the truck bar and the supports when the door is open.

The invention consists primarily in an elevator door embodying therein a vertically movable section adapted to descend below the sill when open, said section having a metal sheathing and an angular frame enclosing and projecting beyond same, suspension means for said section, a truck bar secured to the upper reach of said frame, and an elongated support secured adjacent the sill of the door opening and projecting toward said door section within said frame whereby when said door is open said support will receive the load upon said truck bar and transmit it to the wall of the elevator shaft; and in such other novel features of construction and combination of parts as are hereinafter set forth and described and more particularly pointed out in the claims here-to appended.

In the accompanying drawings, I have illustrated my invention in connection with an elevator door of the counterbalanced type having two vertically movable sections adapted to have movement in opposite directions in opening and closing the door.

Referring to the drawings:

Fig. 1 is an elevation of a door of the type above referred to, parts thereof being broken away, and the door being shown in the open position;

Fig. 2 is a horizontal section above the lintel with the door in the closed position;

Fig. 3 is a vertical section adjacent the sill with the doors in the closed position; and

Fig. 4 is a vertical section similar to Fig. 3 with the doors in the open position.

Like letters refer to like parts throughout the several views.

In the accompanying drawings, I have shown at *a* a portion of an elevator shaft or well having a door opening *b* therein, the lintel of said opening being indicated at *b'* and the sill thereof at *b''*. In the shaft *a* at opposite sides of the door opening, are vertically extending parallel guide rails *c* upon which are slidably mounted the upper and lower sections *d*—*e* of a counterbalanced door, said sections being connected by the suspension cables *f* passing over the pulleys

- f*'. The door sections *d*—*e* are of substantially the same weight so as to counterbalance each other and each is provided with suitable shoes coöperating with the rails *c*.
- 5 Said doors move in substantially the same plane but in opposite directions.
- The upper door section comprises a light angle iron frame *d*' inclosing a corrugated metal sheathing *d*², the frame *d*' being reinforced intermediate the sides thereof by a vertically extending binder bar *d*³ sliding in a suitable shoe *d*⁴ secured at the lintel *b*'. This construction is desirable but is non-essential to the present invention.
- 10 The lower section *e* also comprises a metal frame *e*' of light angle iron inclosing a corrugated metal sheathing *e*². The top bar of the frame *e*' has the web thereof laterally projected from each side of the frame to form extensions *e*³ to which the suspension cables *f* are connected. The frame *e*' is reinforced intermediate the sides thereof, by a binder *e*⁴ having a laterally extended head moving in the shoes *e*⁵ secured at the sill *b*² of the doorway. This binder bar and shoe in addition to holding the door section close to the sill so that the door cannot be swung by a blow thereupon away from the said sill, when closed, serves to prevent the swaying of the door away from the sill when the door is open and loaded trucks pass from the sill to the elevator car. The shoe *e*⁵ also forms a part of the support for the truck bar as will more fully appear hereinafter.
- 15 The lower reach of the frame *e*' is provided with the customary flame shield *g*. The top bar of the frame *e* has secured to the upper flange thereof, a laterally extending plate *h* known as a truck bar, this plate or bar being of a width sufficient to substantially span or bridge the gap between the sill *b*² and the elevator car platform indicated at *i* in the drawing. The plate or bar *h* is of a length substantially equaling the width of the door opening *b*.
- 20 Bolted or otherwise secured to the inner wall of the shaft *a*, below the sill *b*², is a plurality of supports *j*—*j*' adapted to be engaged by the underside of the flange of the top reach of the frame *e*', when the door section *e* is lowered, to sustain the load to which the door and the truck bar are subjected when trucks pass from the floor of the building to the car.
- 25 These supports *j*—*j*' are arranged upon opposite sides of the shoe *e*⁵ and, with said shoe, are spaced sufficiently below the sill *b*² to bring the top of the plate or bar *h* substantially flush with said floor, when the door section *e* is lowered. The supports *j*—*j*' and shoe *e*⁵ form a substantially continuous support extending across the entire floor opening so that stresses applied to any portion of the truck bar, will be transmitted directly to said supports and therethrough to
- the wall of the elevator shaft, thus relieving the door itself from these stresses and preventing distortion of the door or undue stresses upon the guides or upon the suspension cables *f*. Preferably the supports *j*—*j*' are made of channel iron to impart the desired strength thereto and facilitate the attachment of the supports to the wall of the elevator shaft. The lower web of each channel forming the supports *j*—*j*' extends sufficiently close to the flame shield *g* to coöperate therewith in preventing a draft adjacent the sill in the event of fire. To permit the lower reach of the frame *e*' to pass the supports *j*—*j*' and the shoe *e*⁵ the flange *e*⁶ of this frame is recessed at *e*⁶ as shown in Fig. 2.
- 30 When the elevator door is closed the supports *j*—*j*' will coöperate with the flame shield *g* to close the opening between the bottom of said door and the sill *b*². By using a plurality of separate supports *j*—*j*' it is possible to use this structure with a door using a binder such as *e*⁴, this binder with the guides or rails *c* and the door coöperating therewith serving, when the door is open, to hold the top rim of the frame *e*' upon the said support.
- 35 When the door is open the underside of the top bar of the frame *e*' will engage and rest upon the said supports *j*—*j*' as well as upon the shoe *e*⁵ since said supports normally project within the frame *e*' and into close proximity to the sheathing *e*².
- 40 By means of the construction herein described, it is possible to use a light door structure without liability of the same being distorted by reason of heavy loads passing across the top thereof. Furthermore, the guides or rails *c* or the supporting plate *h* therefor, are relieved from the strains of these loads and the suspension cables are relieved from those stresses incidental to the depression of the central portion of the door.
- 45 It is not my intention to limit the invention to the precise details of construction shown in the accompanying drawings, it being apparent that such may be varied without departing from the spirit and scope of the invention.
- 50 By using a plurality of supports *j*—*j*' the same support may be used with doors of different widths and may be so set with relation to the shoe *e*⁵ as to give the desired reinforcement to the truck bar.
- 55 Having described the invention, what I claim as new and desire to have protected by Letters Patent is:
1. An elevator door embodying therein a vertically movable door section adapted to descend below the sill when open, said section having a metal sheathing and an angular frame inclosing and projecting beyond the same, suspension means for said section, a truck bar secured to the upper reach of said

frame, a shoe having a wide face secured to the wall of the elevator shaft adjacent the sill and projecting within the door frame, a vertically extending binder bar carried by said frame and said sheathing, said bar having an enlarged head slidably mounted in said shoe and an auxiliary, laterally extending plane support adjacent said shoe whereby when said door is open said shoe and support will receive the load upon said truck bar and transmit it to the wall of the elevator shaft.

2. An elevator door embodying therein a vertically movable door section adapted to descend below the sill when open, said section having a metal sheathing and an angular frame inclosing and projecting beyond same, suspension means for said section, a truck bar secured to the upper reach of said frame, a shoe secured to the wall of the elevator shaft adjacent the sill, a vertically extending binder bar carried by said frame and said sheathing, said bar having an enlarged head slidably mounted in said shoe, and a plurality of elongated supports secured to the elevator shaft upon opposite sides of said shoe and adjacent the sill of the door opening and projecting toward said door section within said frame whereby when said door section is open, said support will receive the load upon said truck bar and transmit it to the wall of the elevator shaft and said binder bar and shoe will hold the frame of the door in a fixed relation to said support.

3. An elevator door embodying therein a vertically movable door section adapted to descend below the sill when open, said section having a metal sheathing and an angular frame inclosing and projecting beyond same, suspension means for said section, a truck bar secured to the upper reach of said frame, a flame shield carried by the bottom reach of said frame and projecting toward the wall of the elevator shaft, and an elongated channel support secured to the elevator shaft adjacent the sill of the door opening and projecting toward said door section within said frame whereby when said door is open, the upper flange of said channel support will receive the load upon said truck bar and transmit it to the wall of the elevator shaft and when said door is closed, the lower flange of said channel support will project in close proximity to said flame shield, the lower reach of said frame being recessed to permit it to pass the lower flange of said channel support.

4. An elevator door embodying therein a vertically movable door section adapted to descend below the sill, when open, said section having a metal sheathing and an angular frame inclosing and projecting beyond same, suspension means for said section, a truck bar secured to the upper reach of said frame, a shoe secured to the wall of the elevator shaft, a vertically extending binder bar carried by said frame and said sheathing, said bar having an enlarged head slidably mounted in said shoe, a flame shield carried by the bottom reach of said frame and projecting toward the wall of the elevator shaft and a plurality of elongated channel supports secured to the elevator shaft upon opposite sides of said shoe and adjacent the sill of the door opening and projecting toward said door section within said frame whereby when said door is open, the upper flange of each of said channel supports will receive the load upon said truck bar and transmit it to the wall of the elevator shaft and when said door is closed, the lower flange of said channel supports will project in close proximity to said flame shield, the lower reach of said frame being recessed to permit it to pass the lower flange of said channel support.

In witness whereof, I hereunto affix my signature in the presence of two subscribing witnesses, this 12th day of June, 1916.

BENJAMIN WEXLER.
